DOOR LOCK

Frank R. Collar and Earle D. Grizzard, Los Angeles, Calif., assignors to Adams Rite Manufacturing Company, Glendale, Calif., a corporation of California

Application November 13, 1950, Serial No. 195,174

4 Claims. (Cl. 70—418)

1

The present invention relates generally to a lock mechanism, and is more particularly concerned with locks of the key controlled type, such as utilized for swinging doors, and the like.

It is one object of the present invention to provide a door lock of simple construction, which utilizes only a small number of parts, and in which the parts are so arranged that a reliable compact construction will result.

A further object is to provide in a door lock, novel means for dead locking the lock bolt in protracted as well as retracted positions.

Another object is to provide novel actuating mechanism which will work equally as well with key cylinders of different manufacture, and which is not critical as to the length of cam lever operating arm, or the shape of this arm as embodied in the different key cylinders.

It is also an object to provide a construction in which different types of face plates, namely, curved or beveled, may be utilized, and in which the face plates may be variously positioned by means of spacers of different thickness to meet different installation requirements.

Further objects of the invention will be brought out in the following part of the specification, wherein detailed description is for the purpose of fully disclosing the invention without placing limitations thereon.

Referring to the accompanying drawings, which are for illustrative purposes only:

Fig. 1 is an oblique view showing a door lock embodying the features of the present invention mounted on a swinging door, and a cooperative strike as mounted upon an associated door jamb;

Fig. 2 is a side elevational view of the lock;

Fig. 3 is an end view showing the operative association of the various parts of the lock mechanism;

Fig. 4 is a transverse sectional view, taken substantially on line 4—4 of Fig. 3;

Fig. 5 is a vertical sectional view, taken substantially on line 5—5 of Fig. 3; and showing the parts of the mechanism in unlocked position; and

Fig. 6 is a fragmentary view, similar to Fig. 5, except showing the parts in locked position.

Referring generally now to the drawings there is disclosed in Fig. 1 a door 10 which is operatively associated with a door jamb 11. The door is provided with a lock embodying the features of the herein described invention, the mounted lock having an exposed key controlled cylinder 12 for actuating a bolt 13 supported for recti-

2

linear movement in a face plate 14, secured to the door edge by screws 15—15.

On the door jamb 11, there is mounted a conventional strike 16 which is held in place by securing screws 17—17, the strike having a central opening 18 adapted to receive the bolt 13, when the bolt is in protracted or locked position.

The lock mechanism is operatively mounted and supported within a casing structure composed of spaced side plates 19 and 20 and a spacer plate 21. The side plates are provided along one edge with inwardly turned lugs 22, these lugs being secured by means of suitable rivets 23 to the spacer plate 21, so as to form a rigid frame casing construction. In addition the side plates 19 and 20 are secured adjacent their ends by spacer pins 24 and 25 having their respective ends riveted to the side plates.

Adjacent the spacer pin 25, the side plates are reinforced by inner plate members 26—26, these inner plate members and associated side plates being provided with threaded openings 27 in which the key cylinder 12 may be mounted interchangeably in order to provide key control from the inside or outside of the door, as desired. The key cylinder is of conventional construction and includes a rotatable cam 28 which is positioned between the side plates 19 and 20, and is rotatable in one direction or the other to actuate the locking mechanism to locked and unlocked positions, as will hereinafter be more fully described.

The bolt 13 is fabricated from a plurality of plate members. As clearly shown in Figs. 3—6, the bolt 13 is composed of U-shaped side plates 29 and 30, each of which has spaced legs 31 and 32 defining an elongate open-ended slot 33 therebetween. The side plates 29 and 30, at their bridging end portions, are connected by means of rivets 34—34 to an intermediate spacer plate 35 which cooperates with the adjacent portions of the side plates to form the part of the bolt actively cooperating with the strike 16.

The legs 31 and 32 are respectively connected to the corresponding legs on the associated side plate by means of spacer pins 36—36, these pins each having abutment end flanges 37 thereon.

The bolt assembly is supported for rectilinear movements in one direction and opposite direction to protracted and retracted positions, the bolt extending through registering openings 38 and 39 respectively in the face plate 14 and spacer plate 21. The movements of the bolt structure are guided by means of the spacer pin 24 which is straddled by the legs 31 and 32, a guiding collar 40 being placed between the legs

of the respective side plates of the bolt and is secured to the spacer pin 24 by means of a securing pin 41. The spacer pin 24 thus retains the bolt structure against longitudinal tilting, and the guiding collar 40 retains the bolt structure against lateral displacement. Movement of the bolt structure towards protracted position is limited by means of a stop pin 42 supported in the bolt side plates 29 and 30.

Positioned at one side of the bolt structure, 10 is a locking member 43 which is constructed of plate material and is of U-shape generally, this member having a short leg 44 and a relatively long leg 45 which are in spaced relation and cooperate to define an elongate open-ended slot 15 46 which is in right angled relation to the slot 33 of the bolt structure.

The legs 44 and 45 straddle the spacer pin 24 and thus support the locking member for rectilinear movements in one direction and in opposite direction in right angled relation to the rectilinear movements of the bolt 13. The locking member 43 is cooperatively associated with the bolt structure and carries a projecting pin 47 on its leg 44, which is adapted to seat in space 25 notches 48 and 49 in the adjacent leg 31 of the bolt structure, when the bolt is moved either to its protracted position or to its retracted position. Thus the bolt is deadlocked in these positions. The locking member 43 is normally 30 biased in a direction to seat the pin 47 in the notches 48 and 49 respectively by means of a U-shaped leaf spring 50, one end of this spring being anchored beneath an adjacent lug 22 of side plate 20, and the other end bearing against 35 the adjacent end of leg 44 of the locking member 43.

A common actuating member is utilized for the locking member and the bolt structure. For such purpose, an elongate lever arm 51 is provided at one end with a tubular hub 52 which swingably supports the lever arm upon spacer pin 25 as a pivot. The free end of the lever arm 51, as shown in Fig. 5, is contracted to form a reduced end portion 53 which is positioned between the side plates 29 and 30 of the bolt structure for lost motion movement between the adjacent spacer pin 36 and the inner surface of spacer plate 35 of the bolt structure.

Inwardly spaced from the free end of the lever arm 51, there is provided a pin 54 which projects on opposite side of the lever arm 51, as shown in Fig. 3. The right end of the pin 54, as seen in Fig. 3, is operatively associated with the innermost end of locking member 43, this end being formed with a flat end portion 55 which is connected at its ends with inclined edges 56 and 57 to form an appropriate cam surface which will act during swinging movement of the lever arm 51 to move the locking member against the force of spring 50 and at the same time unseat the pin 47 with respect to the notch 48 or notch 49 with which it may be associated.

The left end of the pin 54 is in the path of movement of the cam 28 of the key cylinder, so that by operating this cam in one direction of rotation the lever arm 51 may be rotated in a direction to move the bolt structure to protracted position and by operating the cam 28 in the opposite direction, the movement of lever arm 51 is reversed so as to move the bolt structure to retracted position. Since the shifting movement of the pin 54 is accomplished by engagement with the side edge of the cam arm 28, it is not critical to the operation if the cam

5

arm is made long or short, or the shape of the arm is varied. Thus it is possible to utilize key cylinders of various manufacture without having to modify their structures.

Fig. 5 shows the parts of the lock in their relative positions for a retracted bolt, and Fig. 6 illustrates the positions of these parts when the bolt is in protracted position. Due to the lost motion connection of the lever arm 51 with the lock bolt structure, it will be apparent that the pin 54 will act on the cam surfaces of the locking member during movement of the lever arm 51 in the lost motion interval, so that the bolt will be unlocked from dead lock condition prior to the operation of the lever arm end portion 51 to move the bolt to desired position.

Since the face plate 14 is separate from the spacer plate 21, it will be apparent that this construction permits face plates of different configuration to be attached to the spacer plate. That is, in some installations, it may be found desirable to utilize a face plate with a convex surface so that the door may be swung both inwardly and outwardly, or it may be desired in the case of doors which swing in one direction to open, to provide a face plate having a beveled surface. Thus the present construction lends itself admirably to flexibility of installation.

Moreover, by making the face plate of separate construction, spacers may be inserted between the face plate and the spacer plate 21 so as to adapt the lock structure of the present invention to various installation requirements. Of course, when such spacers are utilized, it will be necessary to lengthen the bolt structure. This is easily accomplished since the bridging portion of the side plates 29 and 30 may be made of any desired length. This is therefore an additional advantage which is obtained by fabricating the bolt structure from stock materials of plate members, rather than constructing the bolt structure of a single or unitary piece of material.

In the foregoing description, a key controlled cylinder 12 has been shown for actuating the lock of the present invention. It is contemplated, however, that various types of operating handles, which are not of the key controlled type, may be utilized if desired; these handle mechanisms being readily mountable in the opening 27 of the casing structure.

In addition, where it is desired to utilize relatively smaller key cylinders having relatively short cams, such as supplied by certain manufacturers, this may be simply and readily accomplished by providing the mounting opening 27 for the lock 12 at a position more closely spaced with respect to the pin 54, or mount a duplicate of the pin 54 higher on the arm 51.

From the foregoing description, it is believed that it will be readily apparent that the lock structure of the present invention will accomplish the objects as hereinbefore noted.

We claim:

1. A lock mechanism, comprising: a bolt mounted for rectilinear movements to protracted and retracted positions; a pair of notches spaced longitudinally of said bolt; a swingably mounted bolt actuating lever arm having a connection at its outer end with said bolt; a bolt locking member supported for rectilinear movements in directions at right angles to the movements of said bolt, said locking member having a projection adapted to seat in one of the notches in bolt protracted position and in the other of said notches in bolt retracted position; means resiliently bias-

ing said locking member in a direction to seat said projection; a pin carried by said arm; a cam surface on said locking member in the path of movement of said pin; and a key controlled lever rotatable in one direction or in opposite direction into engagement with said pin to release said locking member and actuate said bolt from one of its positions to the other.

2. A lock mechanism, comprising: a bolt mounted for movements to protracted and retracted positions, said bolt having shoulder means spaced longitudinally thereof; a swingably mounted bolt actuating lever arm having a connection at its outer end with said bolt; a bolt locking member supported for movements in directions at right angles to the movements of said bolt, said locking member having locking engagement means arranged to engage one of said shoulder means when the bolt is in protracted position and to engage the other of said shoulder means when the bolt is in retracted position; means resiliently biasing said locking member in a direction to bring said engagement means into engagement with said shoulder means; a pin carried by said arm; a cam surface on said locking member in the path of movement of said pin; and an operating lever rotatable in one direction or in opposite direction into engagement with said pin to release said locking member and actuate said bolt from one of its positions to the other.

3. A lock mechanism, comprising: a supporting structure; a bolt mounted in said supporting structure for movement between protracted and retracted positions, said bolt having shoulder means spaced therealong in the direction of its movement; a locking member supported by said supporting structures so as to have movement transversely of the direction of movement of said bolt member, said locking member having locking engagement means arranged to engage one of said shoulder means when the bolt is in protracted position and to engage the other of said shoulder means when the bolt is in retracted position; a pivot member supported by said structure in a position spaced to a side of said shoulder means; a lever swingable on said pivot member and extending therefrom towards said bolt, the free end of said lever overlapping a portion of said bolt and having lost-motion engagement therewith for moving the bolt into protracted and retracted positions, said lost-motion engagement providing a free movement of said lever in either direction prior to the movement of said bolt by said lever; means of engagement between said lever and said locking member adapted to impart from said lever to said locking member, during said free movement of said lever, a movement of said locking member which will disengage said

locking engagement means from said shoulder means; an operating member movably supported by said structure; and a projection on said lever positioned for engagement by said operating member whereby said operating member will move said lever.

4. A lock mechanism, comprising: a supporting structure; a bolt mounted in said supporting structure for movement between protracted and retracted positions, said bolt having shoulder means spaced therealong in the direction of its movement; a locking member supported by said supporting structures so as to have movement transversely of the direction of movement of said bolt member, said locking member having locking engagement means arranged to engage one of said shoulder means when the bolt is in protracted position and to engage the other of said shoulder means when the bolt is in retracted position; a pivot member supported by said structure in a position spaced to a side of said shoulder means; a lever swingable on said pivot member and extending therefrom towards said bolt, the free end of said lever overlapping a portion of said bolt and having lost-motion engagement therewith for moving the bolt into protracted and retracted positions, said lost-motion engagement providing a free movement of said lever in either direction prior to the movement of said bolt by said lever; a cam on said locking member disposed in the path of movement of said lever and being arranged to impart movement to said locking member, during said free movement of said lever, a movement of said locking member which will disengage said locking engagement means from said shoulder means; and an operating member adapted to move said lever back and forth as required to operate said locking member and said bolt.
